UNITED STATES PATENT OFFICE.

JACOB JACOBS, OF NEW YORK, N. Y.

BRACING FOR SIDEWALKS, &c.

No. 861,655.

Specification of Letters Patent.

Patented July 30, 1907.

Application filed January 29, 1906. Serial No. 298,428.

To all whom it may concern:

Be it known that I, JACOB JACOBS, of New York, in the county of New York and in the State of New York, have invented a certain new and useful Improvement 5 in Bracing for Sidewalks, &c.; and do hereby declare that the following is a full, clear, and exact description thereof, reference being had to the accompanying drawings, in which—

Figure 1 is a plan view of a side-walk embodying my 10 invention; Fig. 2 is a plan view of the bracing of such walk; Figs. 3 and 4 are sections on the lines 3—3 and 4—4 of Fig. 2; Fig. 5 is a view showing the elements of which my bracing is constructed, and Fig. 6 a detail view in cross section, showing the provision of a non-slipping surface for the braces when used for floors and 15 side-walks.

The object of my invention has been to provide a 20 bracing for side-walks, floors, walls, etc., which shall be strong and cheap, and which shall be readily adapted to cover vault openings of different dimensions with a very small amount of cutting of the elements of my bracing, and shall also be readily adapted to form bracings of different strengths with elements of a single size, and to such ends,—

25 My invention consists in the bracing for side-walks, etc., hereinafter specified.

In carrying my invention into practice, as illustrated in the drawings, I provide main braces A in the form of T or I-beams which are connected by cross-braces B that are preferably in the form of T-beams, or which may be in the form of I-beams. The flanges and webs of the cross-braces are provided with T-shape slots C, of a size adapted to receive a flange and portion of the web of the main braces A. The cross-braces may be shifted along the main braces, to form any desired spacing, so that the bracing shall be as strong or as light as desired. If the cross-braces are placed close together, the bracing will be stronger than if they are placed far apart. The braces may be riveted 30 together, if desired, and either or both braces may be provided with holes a, b, respectively, through which may be threaded wires or rods D for the better support of cement E, when the latter is used to fill the spaces between the bracing to form a side-walk or wall. The 35 cement locks the bracing together, and prevents any relative movement of the parts. Of course, any other 40

flooring could be used in place of the cement, such as a wooden flooring laid upon the top of the braces. The bracing of a ship may be constructed in the manner illustrated. The cross-braces may be placed either 50 below or above the main braces. The cross-braces may be made in the form of simple bars having no flanges. It will be seen that the portions of the cross-braces which have the T-shape slots formed therein are not materially weakened by the slots when such braces are 55 placed below the main braces, since the flanges b' are placed under compression between the webs a' of the main braces. The portions of the webs c' of the cross-braces which are subjected to a tensile strain are not 60 injured by the slots.

Where my brace is used for side-walks and floor construction, for example, in order to provide a non-slipping foothold or surface, the tops of the beams may be covered with caps F, of lead, which may be in the form of a bar having depending side flanges that embrace the 65 opposite sides of the beams.

Having thus described my invention, what I claim is—

1. A bracing consisting of the combination of braces having flanges, and braces having T-shaped slots opening 70 through to one side thereof, said flanges being received in said slots.

2. A bracing consisting of the combination of main and cross-braces both having flanges, the cross-braces being provided with T-shape slots opening through to the side thereof, said slots being for the reception of the flanges for the 75 main-braces.

3. A bracing consisting of the combination of main braces and cross-braces, both having flanges, said cross-braces having T-shape slots extending through and under 80 the flanges of the cross-braces, said slots being adapted to receive the flanges and webs of the main braces.

4. A bracing consisting of the combination of a series of parallel main braces, that are T-shape in cross-section, a series of flanged cross-braces having T-shape slots extending through and beneath said flanges of the main braces, said main braces being threaded through said cross braces. 85

5. A bracing, consisting of the combination of main braces having flanges, and cross-braces having slots adapted to receive said flanges, said braces having caps applied 90 to their outer edges.

In testimony that I claim the foregoing I have hereunto set my hand.

JACOB JACOBS.
